UNITED STATES PATENT OFFICE.

WILLIAM DUBILIER AND PHILIP DUBILIER, OF NEW YORK, N. Y., ASSIGNEES TO
SPERRY GYROSCOPE COMPANY, A CORPORATION OF NEW YORK.

RADIOSIGNALING APPARATUS.

1,382,177.

Specification of Letters Patent. Patented June 21, 1921.

Application filed July 10, 1916. Serial No. 108,287.

To all whom it may concern:

Be it known that we, WILLIAM DUBILIER and PHILIP DUBILIER, citizens of the United States, residing at 81 New street, New York city, in the county of New York and State of New York, have invented certain new and useful Improvements in Radiosignaling Apparatus, of which the following is a specification.

10 This invention relates to improvements in the method and apparatus for producing high frequency electrical oscillations suitable for wireless communication in which direct or alternating current is used and 15 high frequency oscillations are produced by a simple, light and highly efficient apparatus. It comprises a system of circuits in which electrical energy is impressed through an inductance upon an oscillator or 20 denser charging device in such a manner that these currents are transformed into high frequency oscillations with a high degree of efficiency and these oscillations again in turn are radiated in an aerial wire system. The primary and secondary oscillating 25 circuits although closely coupled, due to the characteristics of the apparatus and its operation, do not react upon each other. A further advantage of my invention is that 30 the two circuits need not be tuned to exactly or near the same wave lengths as is now common in practice. Referring to the drawings, in which what we now consider to be the preferred forms of our invention 35 are shown,

Figure 1 is a wiring diagram of one form of our invention.

Fig. 2 is a wiring diagram of an important modification.

40 In Fig. 1, A is the source of supply; I, inductive resistance consisting preferably of but a single coil N on a magnetic core M; O is an oscillator or condenser charging device comprising electrodes H and E; C is capacity of comparatively small size and L an inductance; K is a switch or hand operated key; B is an aerial and G a ground or counter capacity. A source of current is connected through the inductive resistance, I, 45 which in this case is a powerful electro-magnet. One member H of the oscillator O is mounted on a spring S and forms the armature of electro-magnet I. The spring S may be of any suitable form. It may be in 50 the form of a flat disk, as shown, clamped

around the periphery in the manner of a telephone transmitter. This form of spring possesses the advantage that it will respond to oscillations having widely varying periods. The oscillator is so constructed that 60 the primary circuit IOLKA may be periodically interrupted in such a manner that an arc or discharge will form at O between electrodes H and E. These electrodes are constructed and located so that they will 65 tend to quench the arc or to discharge in such a manner as to strain it to the greatest possible extent; hence charging the condenser C through the inductance L. For this purpose, the electrodes are constructed with 70 very large discharge surfaces or faces compared to their distance of movement and may also be provided with heat radiating fins F.

The discharge faces of the electrodes, it 75 should be noted, are parallel to each other and are moved so as to maintain this relation, so that the arc may form between any points on the two surfaces. In operation, the oscillator vibrates rapidly, the electrodes 80 continually striking together and drawing apart. This movement performs a number of important functions in addition to the function usually performed by the spark gap in wireless apparatus. Among these 85 functions are: 1st, the breaking of the primary circuit and the setting up of inductive currents in winding I, so that it in effect produces a high potential discharge from a low potential circuit; 2nd, the drawing of 90 an arc between them; 3rd, the rapid quenching of the arc by the drawing apart of the electrodes. The strength of the arc, of course, is tremendously increased during this time by the discharge of the condenser 95 C around through the oscillating circuit OCL; 4th, the electrode surfaces are cleaned and flattened by their continual contact with one another. By this means, we are enabled to make use of a very much smaller 100 arc gap than has heretofore been found practicable, since with stationary electrodes metallic particles or scales are apt to form, which quickly short-circuit closely positioned electrodes unless removed. The arc 105 forms, of course, when the gap is infinitesimal, and their rate of separation serves to control in a measure the wave form of both the primary and oscillating circuit currents. It should also be noted that the inductance 110

of winding I serves to limit the current flowing through O when the contacts first close and thereby aids the quenching action and saves power.

5 Another distinguishing feature which results in economy in the use of current and increased efficiency is that after an arc is formed, not only is the current from the condenser used in maintaining the arc, but 10 in addition the current in the primary circuit. The latter current may form an appreciable proportion of the current flowing through the arc, since, as above explained, we use a low voltage primary circuit (say 15 about 100 volts D. C.) and therefore make use of a very much larger current (say, $\frac{1}{2}$ an ampere) than heretofore employed in the wireless sets in which the current used is infinitesimal. By the use of low voltage 20 and a comparatively large current, we are also enabled to charge the condenser in a much less time than ordinarily required. Also, the employing of an appreciable current from the primary doubtless aids in the 25 quick quenching of the arc. This may be readily understood when it is remembered that the condenser discharges first in one direction and then in the other, and that in discharging in one direction it is aided by 30 the inductance of winding I, while when discharging in the other direction, it is opposed by said inductance. It follows that there will quickly come a time when the two 35 currents will be equal and opposite and the arc extinguished.

Electro-magnet I is so constructed that it is placed in very close proximity to the discharge surface at O, so that the arc or discharge will be further quenched. The arc is 40 quenched to such an extent that the condenser C will be charged with the greatest amount of energy and the circuit OCL broken in the shortest possible time so that the oscillations induced in the radiating circuit BLG will continue to oscillate until 45 practically all the power is radiated before any of the energy will be re-induced into the circuit OCL. Hence, we have two oscillating circuits OCL and BLG so constructed that for all practical purposes, the circuit 50 OCL will affect the circuit BLG, but the circuit BLG in turn will not affect the circuit OCL. To further increase the quenching effect electrode H is formed almost entirely of soft iron or the like, with only its 55 face coated with a very thin layer of a good conductor, such as silver. By this means the magnetic lines of force are strengthened at the arc. It should be noted that inductance L performs the functions of both coils L₁ and L₂ in Fig. 2, and that the two oscillating circuits, therefore, remain closely coupled.

In the operation described above, after 60 the arc is formed between the electrodes H

and E, the arc is extinguished in such a minute period of time (of the micro-second order) that the energy which may be stored up on the inductive resistance I will be used again to charge the condenser C. Practically all of this energy will be utilized in 70 charging this condenser for the rapid extinguishing and breaking of the circuit and will practically transform this energy into a potential. The condenser C is of very 75 small value as compared to that usually shunted across the gap of a Rhumkorf coil for the purpose of extinguishing the arc. It is well known that if the large condensers in 80 the Rhumkorf apparatus were made smaller 85 the circuit would not be interrupted but an arc would form and continue to form without actually breaking the circuit. It is our object to utilize this arc and we strain this arc as above described instead of robbing 90 this energy by means of a capacity. Under these conditions, it becomes possible to efficiently produce powerful oscillations with 95 comparatively small potentials and with small inexpensive apparatus, as this circuit 100 OCL can be operated with a direct current source by the above described method of quenching.

These oscillations so produced are induced into another oscillating or radiating system 95 whose natural period of oscillation need not be the same or near the same natural period of the closed or first mentioned oscillating circuit, but may, and in actual practice are found, to vary widely therefrom. 100 It is well known in the art that unless there is fairly efficient radiation, the transmitting apparatus will overheat and cause other defects in a short time of operation. Therefore, it is essential not only for efficient operation but in order to avoid damage to the apparatus, that the radiation should be efficient and in proportion to the amount of power actually applied to the apparatus. 105

We have accomplished the above result 110 to a fairly high degree without the necessity of carefully adjusting and attuning all circuits especially the high frequency oscillating circuit and the high frequency radiating circuit, and can obtain efficient operation 115 and radiation with the circuits which are greatly out of tune, and which remain closely coupled to each other.

In practice, we find our invention especially adapted for aeroplane work where 120 the two circuits often become out of tune. According to our invention the primary oscillating circuit may have a wave length of (say for example) 300 meters and the radiating circuit of 400 or 500 meters and 125 yet we are able to get efficient radiation. Hence, due to this particular system and construction, the primary and secondary inductances may be fixed and no tuning adjustments are needed. 130

An important modification is shown in Fig. 2, where A is again the source of supply; I, electro-magnetic inductive resistance; O, the oscillator; L_1 and L_2 primary and secondary inductances; C, the capacity for radio frequencies; C_1 , capacity of comparatively large value and I_1 , another inductance. We prefer to make the I and I_1 inductances of such values that the current will build up, according to the ordinary exponential curve, to a maximum in a time period which will be approximately equal to the working period of the spring S, and to make the condenser C of such a value that the circuit $C_1 I O L_1$, has a natural time period whose frequency is the same or about the same as the working frequency of the spring S. That is, this circuit may be said to be of audible frequency while the other circuits are of radio frequency. Under these conditions, we could maintain mechanical and electrical synchronism and hence have more uniform operation.

In accordance with the provisions of the patent statutes, we have herein described the principle of operation of our invention, together with the apparatus, which we now consider to represent the best embodiment thereof, but we desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described our invention, what we claim and desire to secure by Letters Patent is:—

1. In a wireless telegraph apparatus, a primary current circuit containing an electro-magnetic inductive resistance, an oscillating current circuit containing a highly quenched oscillator and a radiating circuit, an electrode of the oscillator being movable and affected by the primary electro-magnetic inductance, said electrode being made almost wholly of magnetic material, whereby the magnetic lines of force are brought into close proximity with the gap.

2. In a portable radio apparatus, a primary circuit including an electro-magnetic oscillator consisting of relatively movable electrodes, having very large heat radiating

surfaces, the effective surface area of which is very large compared to the distance of movement, and at least one electrode being almost wholly constructed of magnetic material, thus bringing the magnetic lines of force in close proximity to the gap. 60

3. In combination, a make and break spark gap, a resilient member carrying one of the gap contacts, means fixedly securing 65 said resilient member at, at least, two points oppositely located with respect to and substantially equidistant from the contact carried by said member and a radio oscillating circuit connected to said gap. 70

4. In combination with a radio oscillating circuit, means for insuring the regularity of the tone emitted by said circuit and comprising a vibratory spark gap across which said circuit is connected, said spark gap comprising 75 a pair of relatively movable electrodes and a diaphragm, one of said electrodes being mounted substantially in the center of said diaphragm.

5. In combination with a radio oscillating 80 circuit, means for insuring the regularity of the tone emitted by said circuit and comprising a resilient plate supported at at least two spaced points, a contact carried substantially at the center of said plate so that said 85 contact moves parallel to itself, a co-operating contact juxtaposed to said first mentioned contact, and means for vibrating said first mentioned contact and for impressing an E. M. F. across said contacts, said radio 90 oscillating circuit being connected to said contacts.

6. In combination, a make and break spark gap, a resilient member carrying one of the gap contacts, means fixedly securing 95 said resilient member at, at least, three angularly spaced points substantially equidistant from the contact carried by said member and a radio oscillating circuit connected to said gap. 100

7. In combination, a vibratory spark gap, means constraining one of the contacts of said gap to move parallel to itself, one of the contacts of said gap being constructed almost wholly of magnetic material, a source 105 of magneto-motive force located adjacent said gap and a radio oscillating circuit connected across said gap.

In testimony whereof we have affixed our signatures.

WILLIAM DUBILIER.
PHILIP DUBILIER.
